UNITED STATES PATENT OFFICE.

GIUSEPPE MAZZONI, OF CHICAGO, ILLINOIS.

SAFETY RAZOR AND BLADE HOLDER.

Application filed July 27, 1923. Serial No. 654,115.

To all whom it may concern:

Be it known that I, GIUSEPPE MAZZONI, a citizen of the United States, residing at Chicago, in the county of Cook and State 5 of Illinois, have invented certain new and useful Improvements in Safety Razors and Blade Holders, of which the following is a specification.

This invention relates to certain new and 10 useful improvements in safety razors, and the object of the invention is to provide a device of this kind wherein the blade is positioned parallel with the handle to be employed similar to the blade of a "straight" 15 razor.

Another object of the invention is to provide a razor of the above kind having removable blade tensioning and guard plates, upon the removal of which the handle is 20 adapted for holding the razor blade for sharpening purposes.

A further object of the invention is to provide, in a safety razor, a simple, durable and efficient form of holder for safety 25 razor blades by means of which the latter may be readily stropped and effectively retained while being stropped.

Other objects will appear as the nature 30 of the invention is better understood, and the same consists in the novel form, combination and arrangement of parts herein-after more fully described, shown in the accompanying drawing and claimed.

In a drawing, wherein like reference characters indicate corresponding parts throughout the several views,

Figure 1 is an elevational view of a safety razor constructed in accordance with the present invention.

Figure 2 is a view similar to Figure 1 looking at the opposite side of the device.

Figure 3 is a transverse sectional view taken on line 3—3 of Figure 1.

Figure 4 is a fragmentary longitudinal 45 sectional view taken on line 4—4 of Figure 1.

Figure 5 is a substantially central longitudinal sectional view of the device as it appears when employed as a holder for stropping blades.

Figure 6 is a plan view of a modified form 50 of guard plate which may be employed in lieu of the guard plate shown in Figure 1 when it is desired to use the device for hair cutting purposes, and

Figure 6^a is a sectional view taken on line 55 6^a—6^a of Figure 6.

Referring more in detail to the drawings, the invention embodies a handle member constructed from a strip of suitable springy sheet metal and return-bent intermediate 60 its ends as at 5 so that a pair of adjacent yieldably connected integral handle members 6 and 7 are provided. The adjacent end portions of the members 6 and 7 are preferably transversely curved for strength- 65 ening purposes, as shown clearly in Figure 5, and the free end portions of the handle members are further provided with a plurality of openings 8 and 9 which coincide with each other, the handle member 7 being fur- 70 ther provided with hollow studs 10 about the openings 8 thereof adapted to enter the openings 8 of the handle member 6 when the device is employed for stropping pur- 75 poses, as shown in Figure 5, whereby the 75 handle members are effectively held against lateral play relative to each other. The studs 10 are positioned through the usual openings provided in a safety razor blade when the latter is disposed between the han- 80 dle members, and the latter are effectively latched in clamping engagement with op- 85 posite sides of the blade by means of a spring catch 11 which is formed of a strip of springy metal attached to the handle 85 member 7 and extending inwardly through a slot 12 in the latter and adapted to pass through a similar slot 13 in the handle mem- 90 ber 6 when said handle members are forced together so that the catch 11 will engage 90 the outer surface of the handle member 6 adjacent the slot 13 for releasably retaining the handle members in clamping engagement with a blade 14.

The catch 11 is of substantially L shape, 95 as shown in Figure 5, and will effectively serve its purpose, although permitting ready release of the handle members for removing the blade when the stropping operation is completed.

As shown in Figures 1 to 4, inclusive, the device is provided with a flat guard plate 15 which is toothed along its longitudinal edges as at 16 and is provided with openings for reception of the dowel pins 17 and clamping screw 18 of a curved tension plate 19. The studs 10 permit the passage of the pins 17 therethrough and the handle member 7 is disposed against the inner surface of the plate 19 while the handle member 6 is dis- 100 posed against the outer surface of the guard plate 15, as clearly shown in Figure 3,

whereupon a suitable nut 20 is threaded upon the screw 18 for effectively clamping the parts assembled for use as a double-edged safety razor.

5 In case the device is desired to be used for cutting of hair, a guard plate 21 is simply substituted for the guard plate 15, and this guard plate 21 is similar in form to the guard plate 15, but of slightly larger dimensions, provided with longer teeth, and transversely curved as shown in Figure 6^a.

The outer surfaces of the handle members 6 and 7 are preferably roughened as at 22 to prevent slipping.

15 From the foregoing description it will be seen that I have provided a safety razor and blade holder which is very simple and easy to operate and which can be manufactured at a very small cost, with a blade holder employed for stropping composed of only two parts that can be made by the use of stamps and dies and which are associated with each other in a simple and durable manner.

20 Minor changes may be made without departing from the spirit and scope of the invention as claimed.

25 What I claim as new is:

In a safety razor an elongated handle formed of a single strip of springy sheet 30 metal centrally return-bent to provide a pair of integrally connected normally separated handle members having a plurality of longitudinally aligned opposed openings in the

free end portions thereof, one of said handle members having hollow studs projecting inwardly therefrom about certain of said openings and entering the opposed openings of the other handle member when said handle members are brought together, said hollow studs being adapted to enter the openings of a conventional safety razor blade, said handle members being further provided with aligned transverse slots inwardly of the openings, a catch of substantially L shape attached to the outer surface of one of the handle members and extending forwardly and then laterally through said slots and terminating in a hooked free end adapted to engage the other handle member adjacent its slot for retaining the handle members in clamping engagement with a blade disposed therebetween, a transversely curved tension plate disposed against the outer surface of one of the handle members and having a central clamping screw and end pins projecting through the openings of the handle members, a toothed guard plate disposed between the other handle member and the razor blade and provided with openings through which said clamping screw and pins project, and a nut upon said clamping screw engaging the outer surface of the last-named handle member for clamping the parts together.

In testimony whereof I affix my signature.
GIUSEPPE MAZZONI.
